Inventor,
Paul H. Giessow

By Andrew A. Plumb
His Attorney.

UNITED STATES PATENT OFFICE.

PAUL H. GIESSOW, OF ST. LOUIS, MISSOURI.

SWINGING BABY-CRIB.

1,315,549.

Specification of Letters Patent. Patented Sept. 9, 1919.

Application filed July 16, 1917. Serial No. 180,709.

To all whom it may concern:

Be it known that I, PAUL H. GIESSOW, a citizen of the United States, and a resident of St. Louis and State of Missouri, have 5 made and invented certain new and useful Improvements in Swinging Baby-Cribs, of which the following is a specification.

This invention relates to an improved swinging baby crib, and has for its primary 10 object to provide a swinging crib which can easily be converted into a suspended or swinging seat in which the baby is securely held in place by extending its legs through the apertures in the bottom of the crib, and 15 is provided with a table or shelf upon which the baby may place toys and the like.

With the above and other objects in view my invention consists in the novel features 20 of construction, combination and arrangements of parts to be hereinafter more fully described, claimed and illustrated in the accompanying drawing in which—

Figure 1. is a perspective view of my device used as a seat.

25 Fig. 2. is a front view used as a seat.

Fig. 3. is a side view used as a seat.

Fig. 4. is a side view of the device used 30 as a sleeping crib or bed.

Fig. 5. is a perspective view of the device 35 used to convert the crib into a seat.

Fig. 6. is a detail of the supporting means.

Referring to the drawing, 1. designates the crib body constructed of canvas, or any other strong washable material, and which 40 is preferably of an oblong shape which is supported by any suitable means, such as stitching, to a heavy wire frame, 2. which is held together by welding or other suitable means, and having eyes 3 and 4, formed on either side of the frame diametrically opposite each other, for the purpose herein- 45 after described. The body part 1 has the upper canvas cut away as at 5 to allow the frame to be exposed to admit of the sup- porting means 6 and 7 to be attached thereto.

These supporting means 6 and 7 are at all bearing parts reinforced as clearly shown at Fig. 6; and the supporting means 6—6 are slightly longer than 7—7, which tends 50 to balance the crib when the baby is sitting in it and also tends to elevate the child's head when in a reclining position.

The crib can readily be converted into a

seat by bringing rod 8, which is pivoted or fastened in eye 3, up under the frame 2 and 55 slightly springing this frame outward, so that the eye formed in it at 4 will slip over the end of the rod 8. This rod then forms a supporting means for the canvas or covering of the front part of the crib, which is 60 drawn taut over the rod by the weight of the child, forming a shelf or table 9.

The apertures 10 for the legs are so located in the body part 1 that when used as a seat they will allow the child to assume 65 an easy, natural sitting posture.

What I claim is:

1. A device of the class described, comprising a rectangular wire frame having a loop in one of its side portions, a bag suspended from said frame, a rod pivotally mounted on that side of the frame opposite to said loop and of greater length than the width of the frame, the resiliency of the frame permitting the introduction of the 70 end portion of the rod through the loop, whereby when the rod is so introduced above the bag it constitutes a protection device for the purpose specified, and whereby when the rod is so introduced below the bag it supports the central portion of the bag for the 75 purpose specified, there being a pair of openings in one end of the bag for the accommodation of a child's legs, and means for supporting the frame, substantially as de- 80 scribed.

2. A device of the class described, comprising a rectangular frame of resilient material, a bag suspended therefrom, a rod pivoted to one side of the frame and adapted 90 to engage the other side thereof, the resiliency of the frame permitting such engagement, whereby when the rod is so engaged above the bag it constitutes a protection device for the purpose specified, and whereby 95 when the rod is so engaged below the bag it supports the central portion of the bag for the purpose specified, there being a pair of openings in one end of the bag for the accommodation of a child's legs, and means for supporting the frame, substantially as 100 described.

3. A device of the class described, comprising a rectangular frame of resilient material, a bag depending therefrom, a rod 105 pivoted to one side of the frame and adapted

to engage the other side, the resiliency of the frame permitting such engagement either above or below the bag for the purpose specified, there being a pair of openings in 5 one end of the bag for the accommodation of a child's legs, and means for supporting the frame, substantially as described.

Signed at St. Louis and State of Missouri this 13 day of July, A. D. 1917.

PAUL H. GIESSOW.
